UNITED STATES PATENT OFFICE

2,435,683

TRAFFIC SIGNALING SYSTEM

Peter Hinshelwood, Chicago, Ill.

Application February 24, 1944, Serial No. 523,646

4 Claims. (Cl. 177—337)

1

My invention relates to a signal system or device which while primarily adapted and intended to operate traffic or "stop" and "go" lights, including amber or "caution" lights, lights with indications, arrows, or wordings to indicate turns, when pedestrians will walk, or otherwise, at street intersections, and as a controller or timer in connection therewith, is, also, adapted for store window display, such as to show, throw, direct or reflect colors toward or at articles on exhibit, flash lights or the like, and is superior to those in use or on the market doing comparable work because it is more simple and more economical to produce and operate, in addition to being more efficient, reducing arcing and its disadvantages, and eliminates large and expensive devices with a large number of expensive and moving parts, such as adjustable fingers and contacts, cylinders, discs or barrels on which contacts are used, relatively heavy and large motors, rheostats, ratchets, reducing gears, solenoids, etc., which, of course, render present devices very cumbersome, expensive and difficult to maintain.

With the present signal systems, when the operating motor or motors, stop from any cause, it usually happens that the opposite signals such as red and green "stop" and "go" signals, or the yellow or amber, and turn arrows or indications and walk signals, are left set against one another in bewildering or contradictory relation in opposite directions at intersecting streets or traffic lanes and thereby cause serious traffic accidents especially during hours of darkness. A very important object of the present invention is to eliminate such conditions and avoid accidents, in that, instead of waiting until such other devices can be repaired, as at present, my system is so designed that should the operating motor stop for any reason, as by burning out, or resulting from the blowing of a fuse, or other disruption in the circuit or flow of electrical current, the device will automatically disconnect the red and green, or other direction lights, and set all opposing yellow or amber lights in operation to flash at desired intervals, usually every second, or from 50-60 flashes per minute, or otherwise, as desired, so that warning or "caution" signals or indications will be given to drivers of vehicles and pedestrians approaching an intersection in any and every direction, thereby eliminating accidents.

Also, the setting of such signals may be easily and quickly accomplished in an emergency, or at any time or hour, by breaking or interrupting the circuit or current flow to the operating motor,

such as by removing a fuse, and restoration by replacing the fuse, repair or replacement of a part, simply and cheaply effected to cause normal operation of the system and signals.

5 Another object of the invention is to greatly simplify the construction and reduce the cost of production and maintenance of signal systems and devices for the purpose of the present invention, especially as applied to traffic timers, regulators or controllers, so that the same will be reduced and simplified to a minimum.

Another object is to eliminate the use of parts, such as contacts, cylinders, rheostats, or the like where slow make and break of the circuits results

15 in arcing of the electrical current with carbon deposits and burnouts, or derangements or disruptions of the circuits and damage or injury to the parts of the equipment, by employing quick make and break switches, preferably of the 10 ampere, 110 volt, totally enclosed micro-type,

20 which are small, economical and reliable as well as unlikely to get out of working order and by which the timed relation of the signal operations may be easily regulated by the operation of the

25 switches from cams on a shaft directly coupled to the motor and driven at a very slow speed, such as 1 R. P. M. preferably by a synchronous motor, the combination of such motor and switches going to make a more thoroughly dependable and trouble free signal system and apparatus or device,

30 so as to properly operate almost indefinitely without derangement or disrepair.

Another object is to provide a construction by which a series or pairs of opposed series of

35 switches may be operated from a single shaft and cams, driven by a single small slow speed motor, so as to exhibit any desired number of signals in any desired sequence by simple adjustment, such as green for "go," red for "stop," yellow or amber for "caution" or prewarning before stop or go, "walk," right or left turn arrows or indications, or any other special signal.

Another object is to provide for and permit the

45 use and operation of the device and system by a synchronous slow speed motor directly coupled to a shaft which rotates at 1 R. P. M. and having cams operating 4, 8, or any number of totally enclosed quick-make and break micro-switches of

50 10 ampere capacity, or otherwise; or in the event that the load is too great for the capacity of the switch, because of intricate traffic conditions at particular intersections, certain of the switches, or all of them, may instead of carrying the load,

55 only be used to simply and exclusively control

or operate one or more relays through which electrical current may be fed to a larger load than the switches will safely take, or it is desired to place thereon, such as a large number of lights or other signals, which may embrace any type of discernible signal, either visual or audible, and operate in connection with any desired number of signals or signal heads containing the signals or lamps, as may be required at certain or unusual intersections, and still provide a dependable and relatively trouble-free signal system.

Still another object is to provide an automatically operative emergency equipment or arrangement whereby should the normal system, including the red, green and yellow, "stop," "go," and "caution" lights or warning lights fail to operate or function as intended for normal traffic conditions, which would be very rarely, the ordinary yellow or amber "caution" lights, which are a part of and incorporated in the system to normally indicate to approaching traffic, changes in signals or traffic conditions, will be automatically set to intermittently operate or flash as blinkers simultaneously with each other, but against each other at opposite sides of an intersection, as warning or "caution" lights independently of the red and green, or "stop" and "go" lights, but after all of the lights, including the red "stop" and green "go" lights, as well as the yellow "caution" lights, are first extinguished, so that the same yellow or amber lights will again be immediately or instantaneously set in operation independently as blinkers and may be used for both signal indications, or traffic conditions without requiring separate amber or yellow traffic lights therefor, thereby providing a safety element which is lacking in every other signal system in use at the present time. This gives the necessary margin of safety by automatically putting into operation all amber light on that intersection and flashing said amber lights at proper intervals, such as every second, or 50 times per minute, or at other desired intervals, when for any reason the operating motor should stop. These amber lights will continue to flash indefinitely for hours or weeks, until the blown fuse or the defective operating motor is replaced, or other repair made to correct the trouble, which has caused disruption of the circuit. Thus, when the system would fail, as by stopping of the operating motor, instead of the confusion which now exists with red and green lights from opposite approaches of an intersection being set against each other, or continuing to be lighted, thereby causing accidents, especially at night, my device will immediately kill or extinguish those lights, leaving only the amber lights, flashing intermittently or working as blinkers, thus avoiding accidents. The system may be easily, quickly and economically set or restored to normal operation.

Another object is to provide automatically operative means to cause intermittent operation or flashing of the amber lights as blinkers for definite or predetermined periods or hours of each day or twenty-four hour period, when traffic is practically nil, or light, such as at night or between twelve midnight and five or six a. m., or at other desired times, by positively and intentionally opening the circuit to the normal signal operating motor, or otherwise, during such periods while allowing normal signal operation during the remaining or other periods, or hours, in accordance with traffic conditions.

Further objects and advantages will appear and be brought out more fully in the following speci-

fication, reference being had to the accompanying drawings, in which:

Fig. 1 is a plan view of the control or timer of the signal system or device, mounted on a panel adapted to be enclosed in a casing or housing.

Fig. 2 is a sectional view taken on the line 2—2 of Fig. 1.

Fig. 3 is a diagram of the electrical circuit embodying the signal system or device in normal operation at intersecting traffic lanes or streets.

Fig. 4 is a view similar to Fig. 3, showing the position of the parts for operating the flasher signals, with a slight modification of the circuit.

Fig. 5 is a fragmentary plan view of the motor-driven cams, showing a micro-switch arrangement, and

Fig. 6 is a sectional view taken on the line 6—6 of Fig. 5.

In accordance with the present signal system or device, the controller or timer is positioned in any desired relation to, or distance from, the signals controlled thereby and in any desired number, usually with posts having signal heads or boxes housing the lights and colored lenses, or reflectors, or the bulbs may be colored. The casing or housing of the controller encloses a frame, including spaced parallel plates 10, adjustably connected by rods or bolts 11, suitably anchored to a panel 12, as at 13, and having bearings 14 for a cam shaft 15 directly coupled at one end, as at 16, to the adjacent inner end of the rotor shaft of a motor 17, which may be mounted on and insulated from one of the plates 10.

This motor is a self-starting synchronous motor, preferably 1 R. P. M., for driving the shaft 15 at the same speed. Removably and adjustably fixed to the shaft 15 are any desired number of cams, preferably of insulation, dielectric or plastic material, such as Bakelite, hard rubber, composition, hide, or metal, or otherwise, such as cams 18, for red and green or "stop" and "go" lights 20 and 21, and cams 19 for yellow or amber lights 22 for "caution," or indicating a change in the signals, or, there may be other lights or signals, visual or audible, such as left or right turns, or arrows designating the same, "walk" for pedestrians, or otherwise.

These signals or lights are usually set in signal heads or casings on posts at the various corners, 50 or otherwise suitably mounted at an intersection with green facing one way, and red facing another way across the intersection, opposing one another, and operating on the same circuit, assuming that the timed operation thereof is the same, the number of signals varying with the number of intersecting highways, streets or traffic lanes. Any number of such cams may be provided on and fixed to the shaft 15, the contours thereof depending on the lengths and timing or sequence of the signals.

Rigidly mounted on supporting rods 23, adjustably clamped to the plates 10 in slots 24 for adjustment toward and away from the cams 18 and 19, with spacing sleeves 25 therebetween, 65 are a plurality of switches 26, so as to vary the coacting relation of the switches and cams which are aligned therewith to insure proper operation of the switches.

The switches 26 are preferably micro-switches, 70 such as shown in Patent No. 1,960,020, and may be of the 10 ampere, 110 volt, totally enclosed quick-make and break type, or of other capacity, enclosed in insulation, dielectric or plastic casings, and having metallic spring-operating arms 75 or levers 27, shown extending upwardly and out-

wardly, spring-held in normally open positions of the contacts thereof, and adapted to be engaged by the cams 18 and 19 and pressed inwardly to close the same in certain positions of the rotation of the cams with the motor-driven shaft.

These switches may be arranged in a single series, spaced apart in a row longitudinally and at one side of the shaft 15 and parallel thereto, to be operated in proper sequence or timed relation, in accordance with the desired timing or setting of the various signals, audible or visible, such as lights or bells, for operation by the similarly spaced cams 18 and 19 on the shaft 15, as shown in Fig. 1 of the drawings. However, as shown in Fig. 5, the switches may be arranged in pairs of opposed series, or rows, spaced apart as described, on opposite sides of the shaft 15, including the switches 26, operated by the cams 18 and 19, and an additional series or row of switches 26' mounted on similarly supported adjustable rods 23, with spacing sleeves 25', on the opposite side of, and parallel to the shaft 15, and the rods 23, to be operated by similar cams.

The switches 26' may be operated by additional cams 18' and 19' on the same shaft, operated by the same motor directly coupled to the single motor shaft, as described. The purpose of the additional row of switches operated by additional cams on the same shaft, is to operate a larger number of different or additional signals where required, such as left turns, or arrows, "walk," or otherwise, or where three or more streets intersect, and at the same time permit the use of a single operating motor shaft with a short and compact arrangement of the parts in a small housing.

The circuit of line wires 28 and 29, usually of a 110 volt, sixty cycle, A. C. current supply, has its neutral side or line 28 connected by a conductor wire 30 to one end of the magnet winding, or coil 31 of a normally closed multiple, or three-pole double-throw relay 32, the armature 33 of which is suitably held in one direction, as by a spring, or gravity, away from the magnet, so that its pivoted contact arms 34, 35 and 36 are normally held against cooperating contacts 37, 38 and 39, and away from opposed spaced contacts 40, 41 and 42, which may be the terminals or binding posts of the relay leading to the respective contacts.

The phase side or line 29 has a control switch 43 interposed therein, and wire connections 44, 45, 46, 47 and 48 leading therefrom with interposed protecting fuses 49, which may be of the plug, or other suitable type. Wires 46, 47 and 48 are connected to the contact arms 34, 35 and 36. The wire 45 connects to one terminal or binding post of the motor 17, which has its other terminal connected by a wire 50 to one end of the magnet winding or coil 51 of a normally closed single-pole single-throw relay 52. The other end of the coil 51 is connected by a wire 53 to the neutral line wire 28.

Wire 44 connects to one terminal or binding post of the relay 52, as represented by contact arm 54 thereof, which arm is spring, or gravity held, against the contact 55 spaced from the magnet 51, and has a wire 56 connecting it to the other end of the magnetic coil 31. The switch 43 may be an ordinary snap, or knife switch; or the like, no oil switches being necessary, as required with most of the present devices, to avoid arcing.

Line 28 is, also, connected to one side of each

of the various signals, or lights 20, 21 and 22, which are set with the green lights of one street opposing the red lights of an intersecting street, and vice versa, with the amber, orange, or yellow lights coming on before the green lights on one street are changed to red, and the red lights of an intersecting street change to green, in any suitable sequence, depending on the traffic conditions or number of intersecting streets, as will hereinafter be explained.

Wires 57 connect the contacts 37, 38 and 39 to one terminal or binding post of each of the respective normally open switches 26, as represented by contact arms 27, to be actuated by the cams 18 and 19. These operating or contact arms 27 are normally spaced from contacts 58 of the switches 26, and contacts 58 are connected by wires 59 to the other binding posts or terminals of the various signals or lights 20, 21 and 22, as clearly seen in Fig. 3 of the drawings.

Wires 60 and 61 connect wires 30 and 56, leading to the magnetic coil 31 of the relay 32, to the terminals of a small self-starting synchronous motor 62 which, like the elements 32, 43, 49 and 52, is mounted on the panel 12. The motor 62 may operate at 25 R. P. M., or other desired speed, and is mounted on a plate 63, secured to panel 12, as at 64. The rotor shaft 65 of the motor 62 carries a double-acting oppositely tapered, or substantially diamond-shaped cam 66, with rounded ends, which is set between and acts in opposite directions against the operating contact arms 67 of micro-switches 68, which are similar to arms 27, and switches 26 and 26', respectively.

Switches 68 may be mounted on plate 63 for adjustment toward and away from each other and relative to the cam 66, in the same manner as the switches 26 and 26' are mounted on the plates 10. They are shown mounted on the bolts or rods 69 at the slots 70, so that the switches 68, and more especially the arms 67 thereof, will be properly engaged by the cam 66 to properly actuate the switches to open and close them simultaneously, or in any other desired sequence for operating the yellow or amber "caution" lights or signals 22 at opposite intersections as flashers or blinkers.

As shown, the arms 67 and switches 68 may be set in divergent relation to each other toward the top, or free ends of the arms, as best suited to their operation. The terminals, or binding posts of the switches 68, represented by the contact arms 67, are connected by wires 71 to the wires 59, leading from the contacts 58 of the switches 26, each connected to the yellow or amber "caution" signals or lights 22 at opposite sides of the intersection.

The other terminals or binding posts of the switches 68, as represented by contacts or arms 72 are connected by wires 73 and 74 to the contacts 40 and 42. The purpose of these connections is to complete the circuit to the emergency relay energizing circuit provided by the relay 32, and its magnet 31, to operate the motor 62 for flashing the yellow or amber "caution" lights 22, as will be more fully described.

Some detail of the switches 26, 26' and 68, and the mounting of the contacts and arms, or levers 27 and 67, is shown in Fig. 2 of the drawings, but further detail may be had by reference to Patent No. 1,960,020, bearing in mind, however, that these switches are normally open and closed by pressing in on the arms or levers 27 and 67. However, attention is directed to the fact that all of these switches are normally open and after

being closed by cams engaging and pressing inwardly on operating arms or levers 27 and 67 to close the switches and the circuits therefor, and then released, will immediately return to open positions.

Also, all of the cams 18, 19, 18', 19' and 66 are preferably mounted on peripherally notched hubs or collars 15, removably and adjustably held by suitable means, such as set screws 16, in desired positions on the shafts 15 and 65, so that the cams may be set to give the desired sequence of operation of the signals or lights.

A suggested desirable sequence during a sixty-second cycle is to have the cams 18 so formed and set, as shown, that the green lights 21 indicating "go" for traffic bound in either direction on one street or highway, are on for thirty seconds, and the red lights 20, indicating "stop," also, controlled by the same cams at their switches 26 for traffic bound in either direction on an intersecting street, or highway, are simultaneously on during the same or any other desired period, and vice versa, so that the signals of all intersecting streets or highways are set against each other.

However, the cams 19, controlling the yellow or amber "caution" lights 22, associated with the green and red lights in the various signal boxes on posts, or otherwise, through their switches 26 are so formed and set that a cam 19 will close its switch 26 and circuit to the yellow or amber lights, indicating a change from green or "go" to red or "stop," will be lighted with the green lights during the last five seconds of the thirty second period, thereby giving the necessary time duration for the traffic to stop before the green lights have been changed to red.

On the other hand, the other cam 19 will close its switches 26 and circuit to the yellow or amber "caution" lights 22, indicating the change from red or "stop" to green or "go," will be lighted with the red lights during the last two seconds of said thirty seconds, or other period, thereby indicating to the halted traffic to prepare to start or proceed with "caution." Also, if desired, a twenty-five-second "walk" signal may be provided with each green signal, starting simultaneously therewith, as by the cams 18' engaging the operating arms or levers 27 of their switches 26' or left turns operating for any desired period or number of seconds at the beginning or end of each green or red signal duration, operated by the cams 18' engaging the operating arms or levers 27 of their switches 26'.

Of course, the cycle and the sequence or time durations of the signals may be varied, as desired, as where more time is given to the traffic on a busy street, arterial highway, or boulevard, and less time to an intersecting street or highway, or where there are more than two intersecting streets or highways, or where any additional signals are necessary or desirable, such as for indicating left turns, "walk" for pedestrians, or otherwise.

Attention is, also, directed to the fact that one switch may be employed in lieu of the two switches 68, by extending the wires 71 from the operating contact arm, or lever 67 to both the amber or yellow light connections 59, and a single wire instead of wires 73 and 74, to both the contacts 40 and 42.

Should the load on the ten ampere micro-switches 26, such as for the green and red signals, or lights 20 and 21, be excessive, or greater than dictated by standard practice, which would keep

the load down below the maximum capacity prescribed therefor, say five amperes, in order to increase the useful life of the switches, or prevent burning out thereof, these switches may simply be used only for controlling or timing the closing of the operating circuits to the lights, and such arrangement is shown in Fig. 4 in which connections 71 are made from the neutral line wire 28 to one end of the magnet windings or coils 78 of normally open single-pole single-throw relays 79. The other ends of the windings or coils 78 are connected by wires 80 to one contact or terminal 58 of each of said switches 26 instead of directly connecting the latter at such points to the lights by the wires 59.

The other contacts or terminals represented by, or to which the arms or levers 27 are connected at the switches 26, and to which the wires 51 are connected, are, also, connected by wires 81 to one contact 82 of each relay 79, and the other contacts 83 thereof are connected by wires 84, which replace the wires 59, to the lights 20 and 21. That is, the wire 51 may be said to be extended to the contacts 82 in addition to connecting to the terminals or contacts indicated by the arms or levers 27.

In this manner, when said switches are closed by the cams 18, the normally open relays 79 will be closed to close the circuit to said lights through said relays 79, instead of through the switches 26, and placing the load on the latter, which are merely used as control means for the desired time duration. When the operating arms or levers 27 of the switches 26 are released, these switches will automatically open to deenergize the previously energized relay coils 78 and open the circuits to said lights.

In the operation of the signal system, or device, with the time or control mechanism as described, the device is set in operation by merely closing the switch 43. When this switch is closed, the electrical current from the supply line 29 passes through the wire 45 and its fuse 49 to the motor 17 and back through the wire 50 to the magnet 51 of relay 52, and then through the wire 53 to the line 28. This will start the motor 17 and revolve the shaft 15 and cams 18 and 19 at 1 R. P. M., or any speed required, simply by changing the motor.

This also, energizes the magnet 51 to open the normally closed relay 52 by pulling over the armature contact 54 away from the contact 55 against which it is normally engaged in the closed position, as shown in Fig. 4, to the position shown in Fig. 3. As the motor 17 continues to rotate, the shaft 15 and the cams 18 and 19 will revolve therewith at the same speed to close the switches 26 in the desired sequence and for such time intervals as desired, which may be as heretofore explained.

Thus, the cams 18, by closing their switches 26, will simultaneously close the circuits to the red and green lights 20 and 21 at opposite sides of an intersection. This will cause the current to flow from line 29 through the wires 46, 47 and 48, and the respective pairs of contacts 34 and 31, 35 and 38, and 36 and 39 to the wires 57, then through the switches 26 by way of the contacts 27 and 58 to the wires 59 leading to the lights or other signals, so that the green lights are exhibited to traffic traveling in opposite directions on one street and the red lights set against the traffic in opposite directions on one or more intersecting streets.

As heretofore explained, during the sixty-second cycle the red and green lights opposing

one another may be on for thirty seconds and the yellow or amber "caution" lights on the same signal posts lighted five seconds before the green lights are extinguished, and the red lights lighted at such points. At the other points of the intersection, the red lights will be lighted at the same time that the green lights of the intersecting street are lighted, and the amber lights associated in the same signal boxes therewith, will be lighted during the last two seconds of the thirty-second period during which the red lights are lighted, so as to indicate when the traffic may proceed before the red lights are extinguished and the associated green lights are lighted.

Thus the cams 19, which operate the yellow or amber "caution" lights will be spaced to operate several degrees behind the cams 18 due to the different radial positions thereof on the shaft 15, and will only close the circuits to the various lights upon striking the operating arms or levers 27 to close the switches 26 against the contacts 58 for the desired time duration determined by the positions and shapes of the cams. The cams, as shown, are made to give the sequence described in connection with a sixty-second cycle.

In the operation just described, the motor 17 is running and the relay 52 is in its open position due to the energization of the magnet 51 causing the attraction of the armature 54 away from the contact 55 and as long as the motor continues to operate, the signals will be operated in their regular sequence to indicate "stop" and "go" and "caution," with the changes in the signals. However, if the motor 17 should stop for any reason, such as because of disturbances of the circuit thereto, assuming that there is no failure in the current supply from the power line, such as by the motor burning out, a short circuit or burning out or blowing of the fuse 49 in the wire 45 leading to the motor 17, the current to the magnet 51 of the relay 52 will be cut off, thus releasing or freeing the contact arm or armature 54, to permit the latter to close against the contact 55 in the normally closed position of the relay 52.

This deenergization of the magnet 51 will close the emergency relay energizing circuit at the conductors or wires 44 and 56, by allowing current to pass therethrough from the line 29 to the three-pole double-throw relay 32 through the wire 56 to the magnet 31, and then back through the wire 30 to the line wire 28. This will attract armature 36 or 33 of the relay 32, causing the respective contacts 34, 35 and 36 to engage the contacts 40, 41 and 42, thereby opening the circuits to the lights through the contacts 37, 38 and 39, and the wires 57, switches 26 and wires 59, so that there will be no current passing to the lights, even should the switches 26 be closed by accidental or other partial rotation of the shaft 15, and parts associate therewith.

Upon the energization of the magnet 31, current will then pass through the wires 30, 60, 56 and 61 to the emergency signal operating motor 62, to cause its shaft 65 to be driven at 25 R. P. M., or other speed desired, and which, as explained in connection with the motor 17, may be varied simply by changing the motor. This will cause the cam 66 to revolve and strike the operating arms or levers 67 of the switches 68 to close the latter through the contacts 72. This will also close the circuits to the yellow or amber lights 22 through the wires 71, which are connected to the wires 59 leading to said lights, and the wires 73 and 74 leading to the contacts 40 and 42. The circuit is, then, traced through the contacts 34,

and 36 and wires 46 and 48 with the interposed fuses 49 from the line wire 29 through the various parts, as specified, and finally from the lights 22 back through the line wire 28.

Thus, as long as the motor 62 continues to operate, the cam 66, secured to the shaft 65 thereof, will continue to revolve so as to strike the operating arms or levers 67 of the switches 68 to simultaneously close the circuits there-through and send the current to the load side of the yellow or amber "caution" lights 22, causing them to flash, or blink, approximately every second, or substantially fifty times per minute, or at any other desired speed, according to the speed of the motor.

Obviously, when the magnet 31 was energized, the regular circuits to the red, green and amber lights were broken, cutting them off entirely, until the amber lights were connected and operated through the emergency circuit by the motor 62, as described. Thus, instead of leaving the red and green lights from opposite directions set against each other at intersections in contrary or bewildering relation, and causing serious accidents, especially during the hours of darkness, my signal system, or device, entirely eliminates such condition due to the extinguishing of the lights, especially the red and green "stop" and "go" lights, and the subsequent flashing of the yellow or amber "caution" lights at opposite sides of the intersection, so that the drivers of cars and pedestrians will be properly warned, and the possibility or probability of accidents definitely eliminated.

Fig. 4 shows the same circuit arrangement as illustrated in Fig. 3, but, with the circuit to the motor 17 open or disrupted through any cause so as to deenergize the magnet 51 and with the contacts or armatures 34, 35, 36 and 54 closed against the respective contacts 40, 41, 42 and 55. However, as heretofore explained, instead of having the circuits to the lights closed through the switches 26 so that the latter must take the load thereon, the switches 26 are merely used for closing the circuits through the relays 19, so that the circuits to the lights, or other signals, will be closed through the wires 81, 84 and contacts 82 and 83 by the energization of the magnets 78, thus relieving the switches 26 of the load for operating the signals, which may be visual or audible, as heretofore explained. Wires 81, 84 are used in lieu of wires 59.

In this manner, either arrangement will permit the use of very light, inexpensive equipment, or parts, which may be economically produced, purchased and maintained, so that there will be a considerable saving in the maintenance of signal systems, or the like, of the character described.

The operation of the emergency yellow or amber lights 22 as flashers or blinkers is the same as described in Figs. 3 and 4 of the drawings, and they will continue to operate individually until the circuit to the motor 17 is reestablished by repair or replacing of the motor or fuse 49 in the wire 45 of the normal motor circuit. Also, it is obvious that the flashers of the emergency relay energizing circuit may be set to operate at any time desired, merely by backing out or removing the said fuse to break the circuit to the motor 17 for special traffic conditions, or when the traffic is light, such as after certain hours at night, or otherwise.

It is, also, to be understood that the parts shown in Figs. 1, 2, 5 and 6, arranged upon the panel 75, may be enclosed in any suitable casing or hous-

ing capable of being opened for obtaining access to the equipment, as is usual in traffic timers or controllers, and that the panel 12 may be arranged horizontally or vertically, as desired.

By changing the circumferential positions of the cams, or using cams of different shape or contour substituted for the other cams, the sequence, or timed relation of operation of the signals may be varied, as will be found best suitable for particular traffic conditions or lighting arrangement. Of course, the fuses 49 protect the various parts of the circuits and in an emergency backing out or removal of any of said fuses, especially in the wires 46, 47, and 48, will permit any of the sets of signals or lights to be thrown out of operation and others operated as desired to meet certain conditions.

Also, the two cams operating the micro-switches to the red and green "stop" and "go" lights may, by merely opening the control switch and loosening the set screws holding said cams on the cam shaft, be slid over out of the way, or path of the two switches which they normally operate, and then, by again anchoring said cams and closing the control switch to the motor 17, the device will operate as a flasher system, even though slowly, unless the 1 R. P. M. motor is replaced by a motor of higher speed, such as 25 R. P. M. or otherwise, as desired. Any number of signal boxes for lights, with any desired signal indications of any number, may be set at the various corners of intersections, or, merely one at the center of the intersection.

In addition to opening or breaking the circuit to the signal-operating motor 17 by removal, backing out, or blowing out of the fuse 49 therein, burning out of the motor 17, or other disruption of the current flow in said circuit to cause flashing or intermittent operation of the yellow or amber "caution" lights 22 at opposite sides of intersecting streets when desired, or in an emergency when the normal system, including the red, green and yellow or amber, "stop," "go," and warning lights, fails and operation thereof for an indefinite period, or until repaired or restored to normal direction signal operating condition in which the "stop" and "go" lights are operating, I may intentionally and automatically break said circuit or cut off the "stop" and "go" lights and intermittently operate only the yellow or amber "caution" lights 22 as blinkers, for definite and predetermined periods or hours of each day, or twenty-four hour period, such as between twelve midnight and five or six a. m., when traffic is practically nil, or light, or at other desired times.

For this purpose a normally closed quick-make and break micro-switch 85 is interposed in the circuit to the "stop," "go" and "caution" direction signal-operating 1 R. P. M. motor 17 and connected thereto in series with the motor 17 and the neutral line 28. This may be done by interposing the normally closed switch 85 in the wire 45, or either return wire 50 or 53. For this purpose wires 86 and 87 from the terminals of the switch 85 are respectively connected to opposite ends of a gap in either of said wires 45, 50 or 53, and shown as the latter. Switch 85 has an operating arm or lever 88 adapted to be pressed in for opening the switch 85 and the normally closed circuit therethrough, to the motor 17 which normally operates the direction signals or lights. Lever 88 cooperates with contact wire 86.

A self-starting synchronous motor 89, revolving at one revolution per day, or every twenty-four hours, and represented by 1 R. P. D., has its

terminals respectively connected to the return or neutral line wire 28 by a wire 90, and either directly to the phase supply line 29 with a separate interposed protecting fuse 49, the same as fuses 5 49, heretofore described, or indirectly thereto through wire 45 to supply current to the motor 89 for operating the same when the circuits thereto and to the 1 R. P. M. direction signal-operating motor 17, are normally closed and the red, green 10 and yellow lights are operating in sequence for normal traffic conditions.

A cam 92 is removably and adjustably fixed to the rotor shaft 93 of the 1 R. P. D. motor 89, in the same manner as the cams heretofore described are mounted on their respective shafts, but in position adjacent to and aligned with the operating arm, or lever 88 of the switch 85 to depress and hold in lever 88 to open the switch 85 and hold it open for definite and predetermined periods, depending upon the length or shape and setting of the cam 92.

As shown, the cam 92 is in the shape of approximately a quarter sector or segment of a circle, with a substantially 90° angle between its radial sides, in which case the cam 92, as it very slowly revolves with the shaft 93 of the motor 89, will be clear or out of engagement with the lever 88, or merely contacting therewith without pressing in the same, for approximately eighteen hours, or three-quarters of a day or twenty-four hour period with normal direction signal operation and in engagement with and pressing in lever 88 to open switch 85 and the circuit to the motor 17 for approximately six hours with only the flashing amber signal operation by the motor 62, but, this may be varied as desired by substituting a cam with a shorter, or longer arc.

The cam may be set to hold in lever 88 and the switch 85 open for six hours, say from twelve 40 midnight to six a. m., or at other hours desired and disengaged from the lever 88, with the switch 85 normally closed for eighteen hours from six a. m. to midnight. Thus, when the switch 85 is left closed, the circuit to the motor 17 will be 45 closed to operate all of the direction signals or red, green and yellow lights 21, 21 and 22 in the normal way during the hours of the day when the traffic is heavy.

When the switch 85 is held open, the circuit to 50 the motor 17 will be broken to cause the intermittent operation or flashing of the yellow lights 22 only, as "caution" or warning blinkers. This is because of the resulting closing of the emergency signal circuit to the 25 R. P. M. motor 62, and the yellow lights 22 through the normally open switches 68, which are instantaneously and intermittently closed and freed approximately each and every second by the cam 65 on the shaft 65 of the motor 62, to cause similarly timed flashing of the lights 22 as heretofore explained.

The cam 92 may be shorter to hold the switch 85 open for less time, say five hours, from twelve midnight to five a. m. and to leave the switch 85 closed for the other nineteen hours, or by having cam 92 longer, the switch 85 will be held open longer, say seven hours, or otherwise, depending on the arc length of the cam and traffic conditions. Also, the hours or times of the day and night when the switch 85 is closed and open respectively, may be varied by adjusting the radial or circumferential position of the cam 92 on its shaft 93, the cam being marked with the hours, if desired, to facilitate the setting or adjustment thereof.

With this arrangement, the normal traffic lights

will be on and operating for definite or predetermined periods or hours each day, or twenty-four hour period, such as in the daytime, and the red and green lights off with only the flashing yellow "caution" lights on and operating for the other or remaining definite or predetermined periods, or hours each day or twenty-four hour period, such as at night. Then, when this arrangement is inoperative with motor 89 not running and the circuit thereof broken, but with switch 85 closed and motor 17 running, normal direction signal operation from cams 18 and 19 will continue.

On the other hand, with motor 17 or both motors 17 and 89 not running and with the circuit of motor 17 broken, the amber lights 22 will flash as blinkers. This arrangement may be omitted when it is only desired to operate the blinkers for indefinite periods, or in case of an emergency due to failure or other breaking of the circuit to the motor 17 intentionally or unintentionally. Also, it will be understood that the parts 78, 79, 85, 89, 92 and 93 will be mounted on the panel 12 in the same manner as the other corresponding or similar parts, such as parts 15, 17, 18, 19, 26, 26', 62, 65, 66 and 68, as heretofore described.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a device of the class described, an electrical circuit, a motor in the circuit, signals in the circuit, normally open switches in the circuit with the signals, said switches having operating levers, a shaft driven by the motor, cams on the shaft for actuating the levers in timed sequence to close the circuit to the signals, a magnetic device normally in open circuit to normally close the circuit to the switches, a magnetic device in circuit with the motor to normally hold the first magnetic device in open circuit and to close the circuit thereto upon opening of the circuit to the motor, a second motor of a different speed than the first motor and in normally open circuit when the circuit to the first motor is closed and placed in closed circuit with the first magnetic device upon opening of the circuit to the first motor and magnetic device in circuit therewith, a normally open switch in normally open circuit with certain of the signals when the first magnetic device is in its normal position and adapted upon opening of the circuit to the first motor to be placed in circuit with said certain signals, and a cam driven by the second motor to engage and close the last-named switch intermittently to correspondingly close the circuit to said certain signals.

2. In a device of the class described, an electrical circuit, a slow speed motor in the circuit, lamps in the circuit, normally open make and break switches in circuit with the lamps, said switches having operating levers, a shaft driven by the motor, cams on the shaft opposing the levers of the switches for intermittently closing the switches in timed sequence to correspondingly close the circuit to the lamps, a relay normally in position to close the circuit to the switches, a

relay in circuit with the motor to maintain the first relay in open circuit when the motor circuit is closed and to close the circuit to the first relay when the motor circuit is opened to thereby break the circuit to the switches, a second motor of higher speed than the first motor in circuit with the first relay to operate when the first motor circuit is opened, a shaft driven by the second motor, a double-acting cam on the latter shaft and opposed quick-make and break switches on opposite sides of the cam and having operating levers intermittently actuated by the cam when rotated to correspondingly close the latter switches, said latter switches being placed in circuit with certain of the lamps when the circuit to the first relay is closed to break the circuit to the first switches and operate the second motor, to intermittently close the circuit to said certain lamps to cause flashing thereof.

3. In a device of the character described, an electrical circuit, traffic signals in said circuit "stop" and "go" signals and "caution" signals, switches in said circuit with said signals, a motor in said circuit, means operated by said motor to actuate said signals at intervals, a second motor, means operated by the opening of the circuit to the first said motor to interrupt the circuit to said "stop" and "go" signals, and complete the circuit to said second motor, and cause said "caution" signals to be brought into the circuit as controlled by said second motor, a third motor in said circuit, and means controlled by said third motor to interrupt the circuit to the first motor and said "stop" and "go" signals for a predetermined interval and then again complete said circuit to the first said motor and said "stop" and "go" signals.

4. In a device of the character described, an electrical circuit, traffic control lights in the circuit including "stop" and "go" lights and "caution" lights, switches in circuit with said lights, a relatively low speed motor in said circuit, means operated by said motor to actuate said switches at intervals to close the circuit to said lights in accordance with a predetermined sequence, a second motor in said circuit of higher speed than the first said motor, means operated by said second motor for actuating the switches to said "caution" lights only, means included in said circuit for completing the circuit to said second motor and said "caution" lights when the circuit to the first said motor is interrupted, a third motor in said circuit of lower speed than the first said motor, means operated by said third motor for discontinuing the circuit to the first said motor and the "stop" and "go" lights for a predetermined interval and then again completing said circuit to said first motor and said "stop" and "go" lights upon the expiration of said interval.

PETER HINSHELWOOD.
